FRANZ WOLF, OF NEW YORK, N. Y.

MARKING OR CUTTING DEVICE.

Application filed May 6, 1927. Serial No. 189,380.

This invention relates to a device for punching and cutting sections from a continuous strip of paper or the like, to serve as meal checks, tickets or receipts and has 5 for its object to provide a portable device which will be simple and cheap to manufacture and convenient for use by waiters, conductors or the like.

With this and other objects in view my 10 invention consists in the novel construction, combination and arrangement of parts as will be hereinafter more fully described and defined in the appended claims.

In the accompanying drawings which 15 form part of this specification and in which similar reference numerals denote corresponding parts Fig. 1 is a front elevation of my device; Fig. 2 a top plan view thereof; Fig. 3 a vertical section on 3—3 of Fig. 1; Fig. 4 a section on line 4—4 of Fig. 3; Fig. 5 a section on line 5—5 of Fig. 3; Fig. 6 20 shows a part of a strip to be cut or punched by my device; Fig. 7 is a cross section on line 7—7 of Fig. 3 and Fig. 8 a vertical section on line 8—8 of Fig. 3.

Referring specifically to the drawings 10 denotes a casing comprising substantially circular front and rear walls 11, 12 joined together by a plurality of cross pins 15, and 25 a substantially cylindrical side wall 13. This casing is formed with an upper extension 10' having a top 14 and which forms a compartment for the accommodation of feeding means, a punching device and a cutting device to be hereinafter more fully described. The paper strip P is adapted to be wound up to a roll P' around a core 19 reel or the like. The compartment 10' is formed with a bottom or base plate 16 over 30 which the strip P is to be fed and which extends from one side of said compartment to an intermediate point thereof and at its inner edge is formed with a transverse slot 16'. This base plate is also provided with 35 two or more bores or apertures 16², 16³ arranged in alignment with one another transversely to said base.

Suspended from the top 14 or otherwise 40 fixed in said compartment 10' is a bracket 50 arm 17 in which are rotatively mounted two vertically superposed rollers 18, 18' extending transversely in the compartment and adapted to be in frictional engagement with one another on a line even with the upper 55 face of the base plate 16. These two rollers serve to feed the strip P from the roll P'

over the base 16. The bracket 17 is also formed with a guide piece 17' whereby the strip P is properly guided from between the rollers 18, 18' to the base plate 16. The 60 latter is also formed with a guide groove 16^a which leads into the recess or slot 10^a formed in the side wall 14 of the casing.

Formed integrally with or attached to the base 16 at the inner edge of the slot 16' is 65 a grooved vertical support 22 suitably fixed to the wall 11 of the casing and extending transversely in the compartment 10'. In the groove 22 of said support is slidably borne 70 and guided in vertical direction a blade or cutter 23 the lower edge of which serves as cutting edge and is preferably formed with saw teeth 23'. The blade as will be herein-after described is adapted to be reciprocated vertically in its guide 22 through the slot 75 16' of the base plate 16, to cut the strip P after a certain length of the latter has been fed over the bottom 16.

Suspended from the top 14 of the casing 80 is another bracket 24 in which is pivotally mounted at 25^a a double armed lever 25 extending transversely in the compartment 10'. The longer arm 25' of said lever has mounted thereon a member 26 which is capable of 85 sliding on said lever longitudinally thereof. Supported on horizontally extending rods 27 slidably borne in the front and rear walls 11, 12 of said compartment is a sleeve 29 arranged adjacent to and at one side of the lever arm 25'. This sleeve movably bears 90 a vertically reciprocating plunger 28 whose upper end extends through a slot 10^b in the top 14 and whose lower end is formed with a cutting or punching edge. This plunger 95 28 is adapted to lie in the vertical plane passing through the openings 16², 16³ of the base 16 and to normally register with either one of said openings, so that when the strip P is fed over the base 16 through the guide groove 16^a thereof and the plunger 28 is 100 depressed it will in cooperation with the corresponding opening punch a hole through said strip. The plunger is formed with a shoulder or member 30 below the sleeve 29 in which member engages a pin 31 projecting from the slide 26. By this engagement 105 the depression of the arm 25' of the lever 25 will cause the plunger 28 to move downwardly and perform its punching operation. By the displacement of the sleeve 29 through 110 the medium of its rods 27, whose ends project outwardly through the front and rear

walls of the casing and are provided with knobs 27^a or the like, the plunger 28 can be shifted from its position over one of the holes say 16² to the position over the other hole 16³ and vice versa to produce perforations on the strip P at different points of its breadth.

Motion to the puncher, cutter and feed rollers is transmitted from a common spindle 21 suitably supported in the front wall of the casing and adapted to be rotated by means of a crank arm 41 fixed on the outer end of said spindle. The inner end of the spindle is extended to form a support for the core or reel 20 of the paper wall P'. The arm 25² of the lever 25 is hooked or pivotally connected to the upper end 33¹ of a radially extending rod 33 which is actuated by a spring 34 and is guided in brackets 32 fixed to the wall 11. The lower end 33² of said rod 33 carries a roller 35 which owing to the spring 34 is held continuously in contact with a cam 36 fixed on the spindle 21 to which is attached or which is integrally formed with a ratchet wheel 37 concentric with the spindle 21. By rotating the latter the cam 36 will operate the rod 33 as a result of which the lever 25 will be swung on its pivot 25^a to operate the punching plunger 28.

Loosely mounted on the spindle 21 is a cog wheel 39 provided at one of its faces with an annular groove 40 having a cam portion 40^a. The blade or cutter 23 is connected centrally by a pin 42 to one arm 43¹ of a double armed lever 43 which is fulcrumed at 43^a to the support 22. The pin 42 projects through a vertical slot 22^a of said support. By the depression of the arm 43¹ of said double armed lever 43 the blade 23 will be moved downwardly through the slot 16^a of the base 16 and cut the strip P.

The operation of said double armed lever 43 is effected from the cam 40 which engages a roller 44 carried by the lower end of a vertical rod 45 movably guided in brackets 46 fixed in said casing. The upper end 45¹ of said rod is pivoted at 45^a to the arm 43² of the double armed lever 43.

The cog wheel 39 carries a spring actuated pawl 38 which cooperates with the ratchet wheel 37 so that when the spindle 21 is turned in one direction said cog wheel will be carried along in the same direction. The annular groove 40 engaging the roller 44 will normally raise the rod 45 and consequently the blade 23. When during the rotation of the cog wheel 39 the roller 44 passes through the cam portion 40^a the rod 45 will be successively and rapidly lifted and lowered as a result of which the cutter 23 through the lever 43 will be caused to perform the cutting operation and thereupon be instantaneously lifted from the path of the paper strip.

Meshing with the cog wheel 39 is another

cog wheel 39^a rotatively supported at 39^b in the casing and which also meshes with a pinion 47 fixed to the lower feed roller 18'. During each full revolution of the spindle 21 the feed rollers 18 and 18' through the medium of the cog wheel 39, 39^a and pinion 47 will be rotated to feed a certain length of the strip P over the bottom 16 until the free end of said strip projects outwardly through the slot 10^a of the casing.

It will be seen that the two cams 36 and 40^a are adjustable relative to one another. When the spindle 21 and consequently the ratchet 37 are turned in the direction opposite to that of the arrow (Fig. 3) the cog wheel 39 will remain stationary while the cam 36 will be rotated and brought either nearer to or farther from the cam groove 40. By this adjustment of the cam 36 relative to cam 40^a the punching operation will be timed in respect to the cutting operation, so that the punching of the strip can be effected at predetermined points of its length.

The upper feed roller 18 is so arranged in its bearings as to be capable of being lifted out of contact with the lower roller 18' so as to temporarily discontinue the feeding of the strip during the punching operation. To this end one of the journals of the upper roller 18 is carried by one arm of a double armed lever 48 fulcrumed at 48^a to the bracket 17 and the other arm of which is connected by a link 49 to one arm of a second double armed lever 50 fulcrumed at 50^a in the casing. The other arm of this double armed lever is formed to a finger 50' adapted to project into the path of the cam 36, so that when said cam passes underneath said finger it will operate the roller 18 lifting it from contact with the roller 18'. A spring 51 tends to constantly hold the roller 18 in frictional contact with the roller 18'.

The object of making the puncher adjustable transversely to the strip is to enable the punching of holes at different points of the breadth of said strip. Thus the strip may have two or more parallel columns P^a, P^b of figures printed thereon in successive series and it may be desired to punch a hole at a figure in any one of said columns. By my invention I am able to accomplish this with the single puncher 28.

Mounted over the outer face of the front wall 11 is a disk shaped dial 57 on which at uniform distances around its marginal edge are applied figures or numbers corresponding to those printed on the strip P.

When the strip P carries two or more parallel columns of figures as shown in Fig. 6, the figures of the different columns are arranged on the dial in a single row following successively one another in alternate manner.

In order to facilitate the finding of the

figure on the dial at which a hole is to be punched I make the dial adjustable and provide a shield 52 covering in one position of said dial one set of figures and in another position thereof another set.

To this end the dial is fixed to a bar 53 extending diametrically over its rear face and tiltably mounted on the outer end of the spindle 21. One end of said bar is connected 10 by a link 54 to one arm of a double armed lever 55 fulcrumed in the casing and the other arm of which is connected by a toggle joint 56 to the sleeve 29 carrying the puncher 28.

15 When the sleeve 29 is shifted transversely to displace the puncher 28 as aforescribed the toggle joint will be collapsed as a result of which the double armed lever 55 will be swung so as to tilt the bar 53 and thereby adjust the dial to the corresponding position. The shield 52 is in form of an annular rim fitted around the wall 11 of the casing and provided with as many apertures 52^a as there are figures in any one column of the strip P.

20 These apertures are arranged to register with the figures on the dial but spaced apart a distance equal to that between each two successive figures corresponding to those of a single set or column on the strip P.

25 The crank arm 41 which is in front of the dial serves as indicator therefor.

The mode of operation will be as follows:

Suppose a check is to be issued to a customer for the amount of \$.45. Assuming the puncher is in a position to punch a hole through the column containing the numeral "45". In this case the figure "45" on the dial will be visible through the shield. The crank 41 is first swung in the direction opposite to that of the arrow (Fig. 3) until it registers with the figure "45" on the dial. During this rotation the cam 40 remains stationary and only the cam 36 is moved whereby the operation of the puncher is timed. 30 On giving the crank 41 a full turn from its adjusted position in the opposite direction the puncher, cutter and feed rollers will be operated in the aforescribed manner and the punched and cut section of the strip can be pulled out from the casing by its outwardly projecting end.

If a figure say "95" located in another column of the strip is to be punched, then the puncher 28 is first adjusted by the displacement of the sleeve 29 in the aforescribed manner. By this adjustment the dial too will be turned to expose the figure "95" through its shield. The operation is then carried out in the same manner as before.

60 It is understood that various modifications may be made in the construction of my device without departing from the principle thereof.

I therefore do not wish to limit myself to the details described and shown.

65

What I claim is:—

1. In a device for marking a longitudinally fed strip, a marker operable at a right angle and adjustable transversely to said strip and means for operating said marker including an adjustable cam for controlling the operation of said marker.

2. In a device for marking and cutting a longitudinally fed strip, a marker operable at a right angle to said strip and adjustable transversely thereto, a cutter operable at a right angle to said strip, two manually operated independent cams for controlling the operations of said marker and cutter, said cams being adjustable relative to one another for timing the operation of said marker relative to that of the cutter, and means for coupling said two cams to cause them to move in unison with one another for the successive operation of said puncher and cutter.

3. In a device for punching and cutting a longitudinally fed strip bearing longitudinally arranged parallel columns of figures, a puncher operable at a right angle to said strip and adjustable transversely thereto, a cutter operable at a right angle to said strip, two manually operated independent cams for controlling the operations of said puncher and cutter, said cams being adjustable relative to one another for timing the operation of said puncher relative to that of the cutter, means for coupling said two cams to cause them to move in unison with one another for the successive operation of said puncher and cutter and means for automatically interrupting the feeding of said strip during the punching operation.

4. In a device for perforating a continuously fed strip bearing longitudinal parallel columns of figures, a puncher operable at a right angle to said strip and adjustable transversely thereto for punching a perforation at any figure in either one of said different columns, a dial bearing the figures of said parallel columns in a circular row and arranged alternately and successively of one another, said dial being adjustable on its central axis, a stationary apertured shield mounted over said dial exposing through its apertures the figures of one of said columns at a time according to the adjustment of said dial, automatic means causing the adjustment of said dial simultaneously with that of said puncher, and means for operating said puncher including a spindle formed with a crank arm which serves as indicator for said dial.

In testimony whereof I affix my signature.

FRANZ WOLF.
